(57) **CLAIM**

The ornamental design for a hub motor for electric bicycle, as shown and described.

DESCRIPTION

FIG. 1 is a right, front perspective view of a hub motor for electric bicycle showing our new design;

FIG. 2 is a left, front perspective view thereof;

FIG. 3 is a right-side elevational view thereof;

FIG. 4 is a left-side elevational view thereof;

FIG. 5 is a rear elevational view thereof;

FIG. 6 is a front elevational view thereof;

FIG. 7 is a top plan view thereof;

FIG. 8 is a bottom plan view thereof; and,

FIG. 9 is a cross-sectional view thereof, taken along line 9—9 of FIG. 3, illustrating the outer surface shapes thereof.
